DISPLAY RACK

Harriet D. C. Gardner, Los Angeles, Calif.

Application March 17, 1952, Serial No. 18,929

Term of patent 14 years

(Cl. D80—9)

To all whom it may concern:

Be it known that I, Harriet D. C. Gardner, a citizen of the United States of America, residing in the city of Los Angeles, in the county of Los Angeles, State of California, have invented a new, original, and ornamental Design for a Display Rack, of which the following is a specification, reference being had to the accompanying drawings, forming a part thereof.

Fig. 1 is a front perspective view of a display rack, showing my new design;

Fig. 2 is a front elevational view of the rack with the cans removed;

Fig. 3 is an end elevational view of the same; and

Fig. 4 is a top plan view thereof.

The broken lines shown in Figure 1 are for illustrative purposes only.

I claim:

The ornamental design for a display rack, substantially as shown and described.

HARRIET D. C. GARDNER.
